UNITED STATES PATENT OFFICE

WILLIAM A. SELLER, OF ARGENTINE, MISSOURI

STATIC ELIMINATOR

Application filed July 1, 1929. Serial No. 374,976.

This invention relates to static eliminators for radio receiving sets which apparatus I claim to be highly effective in the elimination of undesirable noises such as those created by atmospheric disturbances and electrical equipment of various sorts, in the output of any radio receiver to which the device is connected.

With the general object named in view, the invention consists in certain novel and useful features of construction and organization of parts as hereinafter described and claimed; and in order that it may be fully understood reference is to be had to the accompanying drawing which represents certain parts in diagram and other parts in central vertical section.

In the said drawing, where like reference characters identify corresponding parts in all of the figures, A represents a multiple aerial comprising five parallel wires, the two outside wires identified as 1 being connected at one end, the two wires 2 adjacent the outside wires 1 being also connected together as illustrated, while the center wire 3 is not connected to any of the other wires comprising the aerial. B indicates four single pole double throw switches.

Encircled by the dotted line C is any standard radio receiving circuit and necessary apparatus illustrated as being equipped with a suitable loud speaker 5 having terminals 6 and 7. The aerial lead connection for the radio circuit is indicated at 8 and the ground connection at 9.

10 indicates three iron plates and inserted between said plates but protected from contact therewith by silk cloth inserts 11 are the legs of a U-shaped metal conductor 12 having 40 its ends forming terminals 13 and 14, the pile of plates being secured together in any suitable manner and being subjected to the magnetic field of a permanent horseshoe magnet 15.

45 16 and 17 indicate electromagnetic coils mounted on the legs of the U-shaped magnet 18, said electromagnets attracting and repelling a diaphragm 19 which is stressed inwardly or toward the coils by a bowed spring metal plate 20 having a central opening 20a.

The tension of the bowed plate 20 may be altered at will by operation of a threaded cap 21 engaging the housing 21a to regulate the pressure against the diaphragm 19 as will be readily understood.

55 The mechanism above described is connected as follows: Aerial wires 1—1, 2—2 and 3 are respectively connected to the terminals 22, 23 and 24 of the switches B, the fourth switch terminal 25 being connected by a wire 60 26 to the ground terminal 9 of the receiving set.

The upper four terminals 27 of the switches are connected by a wire 28 to the magnet 15, said wire 28 being tapped by a wire 29 leading to one terminal of an adjustable resistance 30, the other terminal of said resistance being connected by wire 31 to an adjustable inductance 32, the other terminal of the inductance being connected by a wire 33 to the 70 magnet 18.

The lower terminals 34 of the first three switches are connected by a wire 35 leading to terminal 13 of element 12, the other terminal 14 of said element being connected by a wire 36 to the aerial terminal 8 of the radio receiver. Tapped off the wire 35 is a wire 37 having its end soldered or otherwise permanently secured to the center of the diaphragm 19 as indicated.

80 The electromagnetic coils 16 and 17 are connected in series by a wire 38, and one of said coils is connected by a wire 39 directly to one terminal 6 of the loud speaker 5, while the other coil 17 is connected by wire 39a to 85 one terminal of an adjustable inductance 40, the other terminal of said inductance being connected by a wire 41 to the second terminal 7 of the loud speaker circuit.

85 Tapped off the wire 28 to the upper switch terminals is a wire 42 which is connected to a permanent ground for the eliminator equipment. The lower switch terminal of the fourth switch is connected by a wire 43 to a second permanent ground.

90 From a consideration of the above it will be evident that with all of the switches in their upper positions all of the aerials, the eliminator apparatus and the radio receiving circuit are connected by the wire 42 to the 100

ground. It will also be apparent that by selective operation of said switches any aerial or combination of aerials may be used for the reception of radio signals, but that in every case the signal must pass through the pile of plates 10-12.

It will be understood that the inductance 40 must be adjusted to accommodate the particular type of speaker 5 employed in the receiving circuit, and that resistance 30 and inductance 32 are adjusted to suit particular conditions in the grounding of the interference.

The inventor at this time is unable to explain just what occurs in the mechanism and circuits shown, but his experimentation has proven that the construction is effective in eliminating extraneous atmospheric and similar electrical noises from the radio receiving circuit.

I claim:

The combination with a radio receiving set and an aerial therefor, of a static eliminator element inserted in series between said set and aerial comprising a metal plate, a magnet so arranged as to affect said eliminator element, a reproducing unit forming a part of the radio circuit, an electromagnet in parallel with said reproducing unit, a diaphragm adapted to be affected by said electromagnet, a connection from the eliminator element to said diaphragm, and a ground connection for said first-named magnet and the core of said electromagnet.

In testimony whereof I affix my signature.

WILLIAM A. SELLER.

CERTIFICATE OF CORRECTION.

Patent No. 1,774,068.

Granted August 26, 1930, to

WILLIAM A. SELLER.

It is hereby certified that error appears in the above numbered patent requiring correction as follows: In the grant, and in the heading to the printed specification, the residence of the patentee should read "Argentine, Kansas" instead of Argentine, Missouri; and that the said Letters Patent should be read with this correction therein that the same may conform to the record of the case in the Patent Office.

Signed and sealed this 21st day of October, A. D. 1930.

**M. J. Moore,
Acting Commissioner of Patents.**
